UNITED STATES PATENT OFFICE.

MILO E. HAMILTON, OF WORCESTER, MASSACHUSETTS.

BOTTLE-STOPPER.

1,132,931.

Specification of Letters Patent. Patented Mar. 23, 1915.

Application filed March 2, 1914. Serial No. 821,873.

To all whom it may concern:

Be it known that I, MILO E. HAMILTON, a citizen of the United States, residing at Worcester, in the county of Worcester and State of Massachusetts, have invented a new and useful Bottle-Stopper, of which the following is a specification.

This invention relates to that type of bottle stoppers provided with a flat top serving 10 as a handle and also serving for the purpose of dislodging a metal cap from the bottle and used for stopping bottles after these caps have been removed.

The principal objects of the invention are 15 to provide a hollow stopper of this kind of a very light weight, and to arrange the parts in such a way, that there will be no chance for the liquid in the bottle to get to the inside of the stopper or in any way become 20 lodged in any depressions or cavities within the stopper.

Reference is to be had to the accompanying drawings in which—

Figure 1 is a front elevation of a stopper 25 constructed in accordance with this invention; Fig. 2 is a sectional view of the same on the line 2—2 of Fig. 1; and Fig. 3 is a transverse sectional view on the line 3—3 of Fig. 1.

Stoppers of this type are exceedingly simple articles of manufacture, nevertheless they have presented difficulties in practice which many manufacturers have attempted to overcome, but which still interfere with the 35 manufacture of the same in large quantities, the distribution through the mails, as well as with the efficiency and desirability of the article of manufacture when in use. The main difficulty is that in attempting to reduce the 40 weight of the article, other disadvantages have been introduced, such as reducing the strength beyond practical limits, and furnishing cavities into which the liquid can come, and thus permitting the liquid to sour 45 and even contaminate the entire contents of the bottle. This invention is designed for the purpose of overcoming these difficulties, and at the same time producing a light, strong, durable and thoroughly sanitary 50 construction which can be shipped at a minimum expense and even sent through the mails at a very low cost.

The stopper is shown of an external form mainly like that which is well known on the 55 market. It is provided with a main body 10 of conical form having a flat end 11 pro-

jecting beyond the surface of the conical portion to form a circular end flange 12. At the top of the conical part it has a flange 13 from the center of which extends the flat 60 handle 14. This handle is provided with an opening 15 having an edge 16 for engaging under the edge of a metallic cap for the purpose of dislodging it in a well known manner. In order to lighten the article the interior of the body 10 is cored out in the casting process, and this core is arranged concentrically in the body of the mold so that the cavity 17 is concentric with the body 10 65 of the stopper. The perforations 18 through 70 the walls of the stopper, which receive the core prints in the casting operation, are arranged in the plane of the handle 14 so that any strength which is lost by the presence of these openings is compensated for by the 75 fact that the handle strengthens the body at the ends of these perforations. This is important because the article preferably is made of aluminum or a light aluminum alloy and considerable strength is required 80 on account of its use for removing bottle caps.

A tube 20 of rubber or other soft and preferably elastic material, as for example cork, is placed on the body 10 of the stopper 85 between the flanges 12 and 13. This tube is intended to fill the entire space between these two flanges and it will be seen that it effectively covers the holes 18 by which the cavity 17 communicates with the 90 exterior, that is, the core print openings. Openings for core prints are necessary in producing a hollow article of this kind by casting, and by having these openings come entirely in the space between the two flanges 95 12 and 13 and stopping them off at a distance from each of the flanges it will be seen that this elastic tube is caused to cover these openings entirely when the tube is in place. This is done without the necessity 100 of any special care in assembling or the addition of a single item of expense. Consequently these holes are effectively sealed and there is no opportunity for the liquid from the bottle to get into them and cause the 105 difficulties which have been mentioned above. This is all the more effective for this purpose for the reason that the rubber tube is always formed of such a size that it will grip the body of the stopper, and consequently its inner surface tends to project 110 into these openings and not only effectively

seal them in that way, but adds still further to the difficulty of turning the tube on the stopper. This advantage is particularly valuable after the rubber tube deteriorates upon continued usage because it is found then that the tube still remains in the same place and effectively seals these openings as long as the tube has any elasticity or life left. Thus the difficulty that would be due 10 to the collection of liquid in the interior of the stopper is entirely avoided as long as the tube is serviceable at all. Moreover if any foreign substance should get into the cavity before the tube is put on, or at any 15 other time, the tube effectively prevents its coming into contact with the liquid in the bottle. This is important because one of these stoppers may be used for a number of bottles in turn, being put away when not 20 in use.

Although I have illustrated and described only a single embodiment of the invention I am aware of the fact that modifications can be made therein by any person skilled 25 in the art without departing from the scope of the invention as expressed in the claims. Therefore I do not wish to be limited to all the details of construction herein shown and described, nor to the particular shape of the 30 parts, but

What I do claim is:—

1. As an article of manufacture, a bottle stopper formed of cast metal and having a smooth conical body provided with a solid

smaller end provided with an integral flange 35 projecting beyond the surface of the body and having a parallel integral wider flange at the other end, said body having openings through the surface thereof to the interior located oppositely between the flanges, a flat 40 handle extending from the second flange, and a rubber tube on said body between the flanges for covering and protecting said openings, the larger flange projecting beyond the surface of said tube and the tube 45 projecting beyond the edge of the smaller flange.

2. As an article of manufacture, a bottle stopper formed of cast metal and having a conical body provided with a solid smaller 50 end provided with a flange projecting beyond the surface of the body and having a flange at the other end, said body being hollow, and having longitudinal openings through the surface thereof to the interior 55 located oppositely, a flat handle extending from the second flange in the plane in which said openings are located, and a rubber tube on said body between the flanges for covering and protecting said openings. 60

In testimony whereof I have hereunto set my hand, in the presence of two subscribing witnesses.

MILO E. HAMILTON
